UNITED STATES PATENT OFFICE.

JOSEPH RALSTON, OF GRANT PARK, ILLINOIS.

KILN.

1,200,132.

Specification of Letters Patent.

Patented Oct. 3, 1916.

Application filed June 30, 1915. Serial No. 37,290.

To all whom it may concern:

Be it known that I, JOSEPH RALSTON, a citizen of the United States, residing at Grant Park, in the county of Kankakee and 5 State of Illinois, have invented certain new and useful Improvements in Kilns, of which the following is a specification.

The present invention relates to improvements in kilns, especially that type adapted 10 for burning tile and brick.

The object of my construction is to provide an arrangement designed to obtain or insure a uniformity in the firing process at all points with respect to the objects to 15 be fired, with a view to obtaining a superior product.

In constructions of this character, the difficulty which is most frequently encountered is the application of the heat or fire so as 20 to be as effective at one point as another, or in other words, so that the intensity of the heat at the top and center of the articles to be burned will be practically the same as at the bottom or the nearest point of application of said heat. Not only is this 25 accomplished by my invention, but a further advantageous feature incident thereto is the control of the source of heat such that the even distribution with respect to the objects 30 contained in the kiln is obtained.

With the above and other objects in view, this invention consists in the construction, combination and arrangement of parts all 35 as hereinafter more fully described, claimed and illustrated in the accompanying drawings, wherein:

Figure 1 is a longitudinal sectional view of a kiln constructed in accordance with my invention. Fig. 2 is a horizontal sectional view 40 taken about on the plane indicated by the line 2-2 of Fig. 1. Fig. 3 is a vertical sectional view on the plane indicated by the line 3-3 of Fig. 2. Fig. 4 is a fragmentary front elevation of one of the firing holes, parts being broken away and shown in section. Fig. 45 5 is a perspective view of one of the damper members disposed for coöperating with a lateral outlet for the heating chamber. Fig. 6 is a similar view of a type of damper or 50 valve for the covering of the chamber. Fig. 7 is a horizontal sectional view on the line 7-7 of Fig. 1.

Throughout the following detail descrip-

tion, and on the several figures of the drawings, similar parts are referred to by like 55 reference characters.

Describing the preferred construction of my type of kiln and referring to the drawings, 1, 2 designate what may be termed, for the purposes of this description, the end 60 walls of the kiln, and 3, 4, the side walls thereof, forming a substantially rectangular chamber or housing in which the plastic material to be fired is adapted to be disposed. The chamber thus constituted is 65 provided with a covering or roof, of any desired construction, but, preferably, as disclosed by the drawings, of arc form. The walls of this kiln are preferably built upon foundations suitably extending below the 70 surface or grade and the said foundations indicated 6, are provided with a suitable number of firing holes or boxes 7 beneath each of which is located the ashpit 8. It will be apparent, particularly by reference 75 to Fig. 2 of the drawing, that a series of these fire holes is arranged in each end of the kiln, and, furthermore, that said fire holes are alternately arranged with respect to each other for reasons hereinafter to be 80 more fully disclosed. The fire holes being arranged below the surface of the ground, obviously protect the fires as is desirable in constructions of this character. At one end 85 a retaining wall 9 is built in spaced relation to the fire holes at this side so as to provide suitable space for firing and removal of ashes. Each fire box 7 communicates with the interior of the chamber through a flue or passage 10 extending longitudinally beneath the floor 11 of said chamber. This 90 floor is preferably constructed of tile, brick or similar material to withstand and retain heat, and arranged within the chamber, at each end thereof is a deflecting wall 12, 95 spaced from the contiguous end wall a suitable distance to allow the fire or heat to pass between the same and into the upper portion of said chamber. The material to be fired is introduced into said chamber through the 100 doorway 13 and arranged between the deflecting walls 12 hereinbefore described. It will be noted also that each of the flues or 105 passages 10 is formed or constructed with a baffle 14 which extends substantially the entire length of the passage, the function of

said baffle being to spread the fire and to insure effective heating of the floor surface above the respective passages or flues.

It may be here explained that the alternate arrangement of the fire boxes at each end of the construction is an especial feature of my invention since it insures the uniformity of heating action at each end of the chamber. The deflecting walls coöperating with the flue passages direct the heat to the upper portion of the heating chamber as hereinbefore mentioned so that said heat is substantially as effective at this portion as at the bottom of the heating chamber beneath which the flues extend. In order to bring or draw the heat and flame, as desired, downwardly, within this chamber and about the objects to be fired, I provide a plurality or series of outlets 15 in each of the side walls 3, 4, these openings communicating with a lateral passage 16 at each side of the construction, said passages leading to a stack or chimney 17. The inner wall for the passage 16, designated 16' is disposed in spaced relation to the fire boxes at this end of the kiln to conform to the spaced wall 9 at the opposite end.

Each of the outlets 15 is provided with a damper of any desired construction, such as illustrated in Fig. 5 and designated 18, said damper being provided with a handle 19 so as to enable the outlet to be properly controlled. Now it will be observed that the fire boxes are located in the ends of the kiln and the diametrically opposite outlets 15 in the sides thereof so that the regulation of these outlets will draw the heat in these lateral directions and thereby obtain a most uniform distribution or circulation of the heat within the firing chamber. If more heat is desired in any one point, the damper corresponding to this location may be opened a greater extent and thereby draw the heat toward said location, as desired, and likewise reduction of the heat at the desired point may be accomplished by closing of the proper damper.

The effective control of excess heat within the chamber is accomplished by the operation of damper valves 20 which are provided for openings 21 in the covering for the heating chamber, one of said dampers being illustrated in Fig. 6. Manual operating members 22 are connected to the dampers in

any desired manner so that when the heat 55 in the kiln becomes excessive said valves may be opened and the excess heat allowed to pass out.

It is preferable to employ with this kiln a suitable number of stay members 23 each 60 suitably connected at its lower end to the foundation walls and at its other end to a tie rod 24.

It will be apparent from the foregoing description that a most effective control may 65 be exercised over the heating action with this construction of kiln and by proper manipulation, a uniform distribution of the heat is secured, necessarily resulting in a better product than is obtainable with the 70 use of kilns not provided with heat sources and outlet controls situated in the manner hereinbefore described.

Having thus described my invention, what I claim as new is:

A kiln of the class described comprising a chamber, a series of heat sources located at one side of said chamber, below the floor thereof, a second series of heat sources similarly located at the opposite side of said 80 chamber from the first series, passages leading from the respective heat sources to the interior of the chamber, opposite deflecting walls in the chamber arranged transversely of the respective passages whereby to direct 85 the heat to the upper portion of said chamber, a plurality of outlets arranged adjacent to the bottom of the chamber at each of the other sides thereof from the heat sources, a stack at one end of the kiln, a flue at each 90 side of the kiln with which all the outlets on the respective sides communicate, said flues passing around one end of the kiln in spaced relation thereto to provide a retaining wall forming an inclosed fire-pit for said end 95 and merging at the base of the stack and communicating therewith, independent damper means for said outlets for drawing the heat to a greater or less extent toward the bottom of the said chamber, a cover for 100 the chamber having exhaust openings, and means for opening and closing the exhaust openings to more or less control excessive heat in the chamber and counteract the draft through the lateral outlets aforesaid.

In testimony whereof I affix my signature.

JOSEPH RALSTON.
